UNITED STATES PATENT OFFICE.

ROBERT MALCOM, OF CHICAGO, ILLINOIS.

EYE-SHIELD.

1,161,061.

Specification of Letters Patent. Patented Nov. 23, 1915.

Application filed November 13, 1908. Serial No. 462,447.

To all whom it may concern:

Be it known that I, ROBERT MALCOM, a citizen of the United States, residing at Chicago, Cook county, Illinois, have invented 5 certain new and useful Improvements in Eye-Shields, of which the following, taken in connection with the drawing, is a description.

My invention has for its object the production of an eye shield designed to be used 10 by persons who are exposed to the wind and dust.

The frame of the shield is constructed of 15 flexible material having means formed integral therewith for retaining the lenses in position, the shield being made so that the edge of the frame will come in contact with the features of the face, but the body thereof will stand away from the face, leaving 20 sufficient room for ventilation and to cover a pair of glasses or spectacles if necessary.

Various modifications in detail touching 25 the construction and arrangement of the different parts of the shield will suggest themselves to persons skilled in the art; my invention is not limited in these regards as the forms illustrated are illustrations of an embodiment of the invention.

In the drawings Figure 1 is a plan view 30 of the blank or frame out of which the shield is constructed; Fig. 2 is a longitudinal section through Fig. 1; Fig. 3 is a side view of the finished shield; Fig. 4 is an end view thereof; Fig. 5 is a plan view of a blank for 35 a modified form of construction, and Fig. 6 is a sectional view taken through a completed shield of the form illustrated in Fig. 5.

In carrying out my invention A represents 40 a blank of flexible material, preferably rubber, out of which the shield is formed. The material is molded into the desired form, having apertures a , a' for the lenses a' . The rim surrounding each of the apertures a is reinforced with the same material and formed into a circumferential groove a^2 , as shown in Fig. 2. The upper edge a^3 of the frame is also reinforced or made thicker and heavier with the same material 45 as shown in Fig. 1, to prevent the shield from being stretched across the fore-

head of the wearer. A notch B is provided in each end of the frame, and a slit b extends a short distance inwardly from the apex of the slot to permit of the edges of 55 said notch being folded over as shown in Fig. 4 and secured together to give the frame of the shield the form shown in Fig. 3, permitting it to extend away from the face. A plurality of apertures b' are provided in the frame to afford a sufficient amount of ventilation. These apertures may be located in any part of the frame desired. An adjustable band of elastic or the like, B' , is secured to each end of the frame 60 and extends around the head of the wearer to hold the shield in place.

In Fig. 5 I have illustrated another form of carrying out my invention in which case the blank C is of the same kind of material 70 having lens rims c made integral therewith and having a groove into which the lenses c' are held. In this case I have provided side lenses for the purpose of giving a wider range of vision, if desired. These side 75 lenses are D-shaped, and extending toward each other from the edge of the frame are the notches d which are overlapped as above described and secured together for the purpose of extending the shield away from the 80 face. Each of the frames is provided with a recess a^4 and d' to fit over the nose of the wearer.

In each of the forms of construction here shown the frame is first formed and each 85 lens is inserted into its groove by simply stretching the elastic material to permit of the lens being fitted into the groove provided for it where it is held in position by the grip of the material itself. 90

I claim:

In an eye shield, the combination of a flexible elastic, ventilated frame formed of a single piece of opaque material and provided with lens holding apertures therein, 95 said frame having grooves formed integrally therein around said apertures, a lens in each aperture, the edge of which projects into the groove and is adapted to be held therein by frictional engagement and to lie in substantially the same plane as the opaque frame surrounding it, a reinforcing strip 100

formed integrally with the upper edge of the opaque frame, and the ends of said frame bent at right angles to the lens holding portion thereof whereby the body of the frame is held away from the face of the wearer, substantially as described.

In testimony whereof I have signed this

specification in the presence of two subscribing witnesses.

ROBERT MALCOM.
